Attorney

UNITED STATES PATENT OFFICE.

ARTHUR A. MCGILL, OF WISNER, NEBRASKA.

WRENCH.

Application filed February 4, 1927. Serial No. 165,892.

This invention relates to an improvement in a wrench, and it has more particular reference to the type wherein the jaws are disposed in parallel relationship with respect to each other and extend at right angles, or substantially so, from the operating handle, the jaws being moved toward and from each other by means of an adjusting nut which serves to operate a screw threaded actuator which is connected to the movable jaw.

In the present embodiment, the jaws are disposed at somewhat obtuse angles with respect to the longitudinal axis of the main handle. The actuator screw has pivotal connection with the movable jaw, and is disposed in substantial alinement with the longitudinal axis of the handle in which it is slidable.

The outstanding improvement is the provision of a pivotally mounted hand-grip which is carried by the handle and which cooperates with a nut on the actuator screw in such a way as to produce pressure. With this arrangement, the movable jaw can be set with rather reasonable accuracy through the medium of the adjusting nuts, after which final and powerful pressure can be brought to bear on the object gripped, in order to insure a firm anti-slipping gripping of said object.

The specific details cooperating to provide the alleged novel structure, will become apparent from the following description and drawings.

In the accompanying drawings forming a part of this application, and in which like numerals are employed to designate like parts throughout the same:—

Figure 1 is a side view with portions broken away and shown in section, disclosing a wrench constructed in accordance with the present invention, and indicating the pressure producing device in extended position.

Fig. 2 is a fragmentary detail perspective view, and

Fig. 3 is an inside edge elevation of the hand-grip.

Referring now to the drawings in detail, it will be seen that the main part or body of the device is generally represented by the reference character 1. This part includes a hollow handle 2 open on one side, an obtuse rigid toothed gripping jaw 3, and spaced parallel furcations 4 extending outwardly beyond the jaw 3. These furcations form guides for the shank 5 of the sliding jaw 6.

It will be noticed that this shank is disposed at right angles to the jaw proper, and also the inner end of the shank terminates in apertured ears 7 (see Fig. 2), and adjacent these ears is a rigid lug 8.

The actuator screw or bolt 9 is disposed in substantial alinement with the longitudinal axis of the handle 1, as shown in the drawings, and this is provided at its outer ends with a connecting end pivot pin 10 which extends through the apertures in the ears 7 and also project outwardly through the diagonal slots 11 formed opposite each other in the furcations 4. In other words, I provide a pair of these slots, one in each furcation or guides, and the slots are disposed one opposite the other. The screw is provided with a lug 8^a, and the coiled spring 12 is connected to this lug and with the first named lug 8 as shown in dotted lines. The adjusting nut which is threaded on the lower end of the actuator screw is represented by the reference character 13, and it has its peripheral portions extending through opposite elongated openings 14 formed in opposed walls of the handle 2.

Closely associated with the details last mentioned is the hand grip 15, which is in the form of a sheet metal stamping of channel-shaped cross section, the same being of a size to swing or telescope between the walls of the handle. At its upper end and on its open side, this hand-grip is pivoted as at 16, and this upper end portion is formed with elongated openings to accommodate the nuts 13. An extension spring 17 serves to normally force the hand-grips to the expanded position represented in Fig. 1.

With this arrangement, it is obvious that by pressing the hand-grip into the handle, a downward stress or pull will be exerted upon the nut 13. In so doing, this will draw the actuator screw 9 and impart additional sliding movement to the movable jaw. Hence, it will be seen that the initial adjustments will be made in a somewhat conventional manner, by adjusting the nut 13, thus moving the jaw 6 to a set position. However, the additional movement provided by actuation of the hand grip 15 will serve to produce a supplemental movement of the movable jaw in order to acquire firm pressure and a reliable anti-slipping grip on the object between the jaws.

Incidentally, it will be noticed that the thickness of the jaw 6 is such as to provide a shoulder at its point of connection to the

shank 5, and to limit the swinging movement in a direction from left to right. Moreover, the action of the spring 12 will serve to hold this jaw in the position represented in the 5 drawing. While the jaw 6 is limited in its movement in a direction from right to left, it is obvious that it is swingable in an opposite direction about the pivot 10. This allows the jaw to cant in order to obtain a good 10 grip on the object, thus rendering it adapted for use as a pipe wrench. However the spring 12 serves to resist the pivotal movement of the jaw and aids in returning it to its normal position.

15 It may not be desirable to maintain a constant grip upon the hand-grip, and in view of this, I provide a retaining device comprising a small bolt 18 having a knurled finger-piece 19 and a nut 20. The nut cooperates 20 with inturned wings 21 formed upon the hand-grip as represented in Fig. 3. With this arrangement, after the hand-grip has been moved to a final pressure-producing position, the adjusting device may be manipulated to hold it in this position.

30 The construction as well as the advantages, and features and operation of the invention will doubtless be clear after reading the foregoing description in connection 30 with the drawings. In view of this a more lengthly description is thought unnecessary.

35 While the preferred embodiment of the invention has been described and shown, it is to be understood that minor changes coming within the field of invention claimed, may be resorted to if desired.

Having thus described my invention, what I claim as new is:—

40 1. In a wrench of the class described, a handle, a rigid jaw extending at an angle from the outer end of the handle, guides carried by said handle and extending outwardly in spaced relation beyond said rigid jaw, the movable jaw including a shank slidably 45 mounted between said guides, a pin and slot connection between said shank and guides, an adjusting screw pivotally connected with said shank, an adjusting nut carried by said screw, and a hand grip pivotally mounted 50 upon said handle and cooperating with said nut for sliding said movable jaw.

55 2. In a wrench of the class described, a hollow handle, a rigid jaw extending at an angle from the outer end of the handle, spaced parallel guides carried by said handle and extending outwardly beyond said

rigid jaw, a movable jaw including a shank 60 slidably mounted between said guides, and movable toward and from said rigid jaw, an adjusting screw connected with said shank and extending down and into said handle, an adjusting nut carried by said screw and co-operable with said handle, a hand grip pivotally mounted in said handle and co-operable 65 with said nut for moving said sliding jaw toward said rigid jaw when said hand grip is pressed into said handle, and an expansion spring interposed between the handle and hand grip for moving the hand grip outwardly when the latter is released. 70

3. In a wrench of the class described, a handle of channel shaped cross section provided at its outer end with a substantially right angularly disposed rigid jaw, portions of the handle extending beyond said jaw and constituting spaced parallel guides, a movable jaw including a shank slidable between said guides, an adjusting screw connected with said shank and extending down between the side walls of said handle, said side walls being provided with openings, a regulating nut carried by said screw and located in said opening, a hand grip fitted telescopically between the side walls of the handle and pivotally connected thereto and having operating connection with said nut, and an expansion spring interposed between the handle and hand grip. 85

4. In a wrench of the class described, a hollow handle of channel shaped cross section, an angularly disposed rigid jaw at the outer end of the handle and on one side of the handle, spaced parallel guide extensions carried by the outer end of the handle and extending outwardly beyond said jaw, said extensions being formed with diagonal slots, a movable jaw including a right angular shank slidably mounted between said extensions, pins carried by said shank and movable in said slots, an adjusting screw connected with said shank and extending down between the side walls of the handle, said side walls having opposite openings formed therein, an adjusting nut on said screw extending out through said openings, a hand grip fitted telescopically between said side walls and pivotally connected thereto and having operating connection with said nut, and an expansion spring interposed between the hand grip and handle. 100

105 In testimony whereof I affix my signature.
ARTHUR A. MCGILL.
